ATTORNEY

UNITED STATES PATENT OFFICE.

CHARLES E. VAWTER, OF PHILADELPHIA, PENNSYLVANIA.

VARIABLE HIGH RESISTANCE.

Application filed July 12, 1922. Serial No. 574,474.

To all whom it may concern:

Be it known that I, CHARLES E. VAWTER, a citizen of the United States, residing at Philadelphia, in the county of Philadelphia,

5 State of Pennsylvania, have invented certain new and useful Improvements in Variable High Resistances; and I do hereby declare the following to be a full, clear, and exact description of the invention, such as 10 will enable others skilled in the art to which it appertains to make and use the same.

This invention relates to variable resistances, and more particularly to variable high resistances especially adapted to be 15 used as grid leaks and for other purposes in connection with radio systems.

In operating radio systems it has been found necessary to provide some means whereby the negative charge which accumulates 20 on the grid of the vacuum tube may be dissipated. If vacuum tubes are used without a suitable grid leak, the operation is not always satisfactory due to the choking effect of the negative charge which accumulates 25 on the grid.

One of the best ways of carrying off the negative charge of the grid is to provide a high resistance in the grid circuit. A high resistance suitable for this purpose should be 30 easily adjustable, and its character should be such that when it is once adjusted the resistance does not vary. The effect of the high resistance is to provide a means whereby the negative charge of the grid may be 35 dissipated at a definite rate. The value of resistance required in any given case depends upon various factors, such as the character of the vacuum tube employed, the voltage impressed on the vacuum tube, the 40 current in the filament and the degree of vacuum. The resistance serves not only as a ready means for dissipating the negative charge, but also as a means for greatly increasing the utility of the vacuum tube.

45 One of the objects of this invention is to provide a high resistance which may be easily adjusted, the resistance being of such a character that when it is adjusted to any given value it remains constant at that 50 value. A further object is to provide an inexpensive variable high resistance which possesses qualities superior to those of any other high resistance.

55 Another object is to provide a variable high resistance unit of an improved construction, such that the resistance unit may

be readily attached to the terminals of a grid condenser, thus providing a combined condenser and grid leak of improved construction and characteristics.

60 The means by which the above mentioned objects and various others are attained will be apparent from the following detailed description which is to be taken in conjunction with the accompanying drawings 65 in which—

Fig. 1 is a top plan view of the improved resistance unit showing the manner in which it is attached to a condenser;

Fig. 2 is a longitudinal section taken on 70 line 2—2 of Fig. 1 showing the construction of the resistance unit and of the condenser;

Fig. 3 is an enlarged transverse section taken on line 3—3 of Fig. 1 showing the details of construction.

75 Fig. 4 is a longitudinal section of a modified form of high resistance unit;

Fig. 5 is an end elevation of the structure shown in Fig. 4.

80 Referring to the drawings, and more particularly to Figs. 1 to 3, it will be noted that the improved resistance unit comprises primarily a container 1, which in the form shown consists of a tube of insulating material. This tube 1 may be made of glass, or 85 of any other suitable insulating material. The inside of the tube 1 is filled with a suitable paste material which constitutes the resistance element of the unit. This paste 2 may be composed of finely divided carbon 90 mixed with tallow, or it may be made of other suitable materials. For example, potassium bichromate may be substituted for the carbon. In fact, any substance may be used which is of a semi-fluid nature and 95 possesses a low electrical conductivity which does not vary when the resistance of the unit is adjusted to any given value.

100 Electrical contact is made with the paste 2 by means of two metallic end pieces 3 and 3', which, as shown in the drawing, are adapted to enclose the ends of the tube 1. These end pieces may have extensions 4 provided thereon by means of which the resistance unit may be mounted on any suitable 105 base. One of the end pieces, for example, the end piece designated as 3' is provided with a small hole 5 concentric with the inside of the tube 1. A suitable metal plunger or pin 6 is provided, this pin being adapted to be inserted in the hole 5 and to be 110 readily moved back and forth in the tube

6. A suitable handle 7 is provided on the end of the pin 6 for the purpose of adjusting the position of the pin with respect to the tube 1.
5. The resistance of the unit may be considered as composed of two components. One component is the resistance of that portion of the paste which is not penetrated by the pin 6, and the other component is the 10 resistance of the remaining portion of the unit comprising that portion of the pin within the tube 1, and the paste surrounding that portion of the pin. It is evident that the resistance of that portion of the tube which does not contain the pin is higher than the remaining portion which does contain the metallic pin 6. It is thus apparent that the resistance of the tube may be varied by changing the position of 20 the pin 6. For example, when the pin 6 is moved to the dotted position shown in Fig. 2, the resistance of the unit is increased, due to the decrease in length of that portion of the pin which is within the tube 1.
25. The resistance unit shown in Fig. 4 comprises a tube 1' containing a high resistance paste 2, similar to that in the tube 1 of the unit shown in Figs. 1-3. The tube 1' is preferably made of fiber or other insulating material, and has metal end pieces 13 and 13'. These end pieces 13 and 13' are adapted to be slipped over the ends of the tube 1' with a pressed fit, the tube 1' being first filled with the paste 2. One of the end pieces, for example, 13' has a small hole or 30 passage 14 in the end thereof.
35. The resistance unit shown in Fig. 4 is of the cartridge type and may be made of standard size to fit any ordinary grid leak 40 sockets or receptacles such as shown at 4'. The unit may be used as a fixed high resistance, or it may be used as a variable resistance. When used as a fixed resistance the opening or passage 14 is preferably 45 sealed. When the unit is used as a variable resistance, a needle 6^a, similar to the needle 6 of Figs. 1-3 may be used, the resistance being varied by varying the position of the needle.
50. I have found that a variable resistance constructed in the manner described above possesses qualities superior to those of any other type of variable high resistance. The resistance of the unit may be easily adjusted to any desired value and when the resistance has been adjusted to any given value, it remains constant. The construction of the resistance unit is very simple and, therefore, resistances of this type may be made 55 in large quantities at very low cost. Each of the component parts of the resistance unit is easy to manufacture. For example, the tube consists merely of a short length of ordinary tubing of any suitable character, such as glass or fiber. The terminals pro- 60 vided at the ends of the tube consist of suitable metal stampings, and the pin 6 may be made of a piece of ordinary wire. The paste material is inexpensive, the elements of the mixture being in common use and only ordinary skill is required to mix the elements in any desired proportions.
65. The improved resistance unit may be made of such dimensions that it may be readily attached to the terminals of a condenser. In the combined condenser and resistance unit shown in Figs. 1 to 3, the improved variable resistance is shown attached to the terminals of an improved condenser, the condenser being of the type disclosed in my co-pending application, Serial No. 562,963, filed May 23, 1922.
70. As described in my co-pending application, the improved condenser comprises a plurality of armatures 8 separated by thin strips of dielectric material. The armatures and strips of dielectric material are enclosed in a metal casing 9, the sides of which are pressed to clamp the armatures in position tightly. Tabs 10 are provided at the ends of the armatures 8, the tabs being connected so that they form the terminals of the condenser. In the form shown in the drawing, the condenser comprises two armatures only. A strip 11 of bakelite or other suitable insulating material is provided between the extensions 4 and 4' of the resistance terminals, and the condenser terminals, the purpose of this insulating material being to prevent electrical contact between the condenser casing and the resistance element. The several elements of the composite unit are fastened together by any suitable means, such as the bolts 12. The bolts 12 also serve as a means for connecting the improved unit 75 in circuit with the other elements of the grid circuit.
80. From the above description it should be apparent that the present invention provides an improved variable high resistance element which is particularly adapted to be used in connection with wireless systems. The improved resistance is particularly adapted to be used as a grid leak, and as a variable high resistance shunt for bypassing objectionable high frequency or momentary currents.
85. It will be understood that the invention is not limited to the particular embodiments shown and described, but is intended to include such modifications thereof as fall within the scope of the appended claims, and the proportions of the various parts and the materials of which they are made may be varied without departing from the scope of the invention as defined in the appended claims.
90. I claim—
95. 1. A variable resistance unit comprising a container, a resistance material within 100
- 105
- 110
- 115
- 120
- 125
- 130

- said container, conducting terminals in constant electrical connection with the resistance material and arranged at the respective ends of said container for transmitting current to and from said resistance material, an electrically conducting member slidably mounted in one of said conducting terminals and extending within said container into electrically conducting relation with the resistance material therein, whereby said member is adjustable longitudinally of said container to cause varying proportions of said resistance material to be traversed by the electric current passing between the terminals of the unit.
2. A variable resistance unit comprising a tubular container, a resistance material within said container, conducting terminals at the respective ends of said container for transmitting current to and from said resistance material, an electrically conducting member slidably mounted for longitudinal movement in the end of one of said conducting terminals and extending into electrically conducting relation with the resistance material within the container to thereby vary the resistance of the unit upon adjustment of said member, and conducting supports for said container, said supports being adapted to engage the ends of said container and one of said supports having a hole for the passage of said adjustable member.
3. A variable resistance unit comprising a container, a resistance material within said container, conducting terminals at the respective ends of said container for transmitting current to and from said resistance material, the said respective conducting terminals having tapered extremities, an electrically conducting member passing through one of said conducting terminals at substantially the apex of the tapered portion thereof and extending within said container into electrically conducting relation with the resistance material therein, whereby said member is slidably longitudinally of said container to cause varying proportions of said resistance material to be traversed by the electric current passing between the terminals of the unit, and conducting supports for said container having apertures for receiving the tapered ends of said container, and permitting the passage of said conducting member.

In testimony whereof I affix my signature.

CHARLES E. VAWTER.
